(No Model.)

G. PFANNKUCHE.
ALTERNATING CURRENT DYNAMO.

No. 407,875.

Patented July 30, 1889.

UNITED STATES PATENT OFFICE.

GUSTAV PFANNKUCHE, OF CLEVELAND, OHIO, ASSIGNOR TO THE BRUSH ELECTRIC COMPANY, OF SAME PLACE.

ALTERNATING-CURRENT DYNAMO.

SPECIFICATION forming part of Letters Patent No. 407,875, dated July 30, 1889.

Application filed December 2, 1887. Serial No. 256,815. (No model.)

To all whom it may concern:

Be it known that I, GUSTAV PFANNKUCHE, of Cleveland, in the county of Cuyahoga and State of Ohio, have invented certain new and 5 useful Improvements in Alternating-Current Dynamos; and I do hereby declare the following to be a full, clear, and exact description of the invention, such as will enable others skilled in the art to which it appertains to 10 make and use the same.

My invention has reference to improvements in alternating-current dynamos, the object being to render such dynamos self-exciting and self-regulating, analogous in this 15 respect to compound constant-potential continuous-current dynamos, whereby the same become adapted for the operation of a system of distribution in which a constant difference of potential is required.

20 My improved dynamo is specially designed for use with such systems of distribution in which the translating devices are in multiple-arc branches derived from a main or trunk line, and in which it is designed to maintain 25 a constant difference of potential at the terminals of the derived branches or working-circuits, which are frequently at great distances from the generator. In such systems the difference of potential at the brushes of the 30 generator is dependent upon the relation of the external resistance to the total resistance in such manner that when the external resistance increases, the difference of potential at the brushes also increases, while at the same 35 time less current is generated in the armature, and when the external resistance decreases, the difference of potential at the brushes also decreases, and more current is at the same time generated in the armature.

40 From this it becomes clear that in a multiple-arc system of distribution whenever one or more working-branches are opened provision should be made to decrease the strength of the field-magnets, and whenever additional 45 working-circuits are closed the strength of the field-magnets should be increased, in order to maintain a constant difference of potential. In continuous-current dynamos this result is accomplished automatically by providing the field-magnets with two sets of coils, 50

one set of which is in series with the armature-coils and the other set in a shunt across the brush-terminals of the dynamo, and the manner in which such dynamos operate to maintain a constant difference of potential 55 under the varying resistance of the external circuit is so well understood by those skilled in the art that a specific explanation is deemed unnecessary.

In alternating-current dynamos it has heretofore been deemed impracticable to apply the principles of the compound continuous-current dynamo, and in order to adapt alternating-current dynamos to the feeding of a system of distribution in which a constant 60 difference of potential is required I have devised certain combinations of such dynamos with separate excitors, which combinations I have made the subject of separate applications. 70

The present invention has for its object the construction of self-exciting alternating-current dynamos in which the same principles are invoked which form the basis of the compound continuous-current dynamo, whereby 75 separate excitors are made unnecessary, the construction simplified, and the effective operation rendered more certain and more economic.

In the accompanying drawing, which forms 80 a part of this specification, I have illustrated my invention mainly in diagram, omitting such details as are readily and necessarily implied.

The alternating-current generator 1 may be 85 of any ordinary or improved construction. It is represented in the drawing as mounted upon a base or platform 2, upon which standards 3 3 of iron are bolted, which constitute the yokes of the field-magnets. The armature 4, which is preferably of the Brush type, 90 is mounted upon a shaft 5, which may be journaled in the standards, and is driven in any suitable manner.

The alternating currents generated in this 95 machine are collected by brushes 6 6, bearing upon collecting-disks 7 7, secured to but insulated from the shaft and having the terminals of the armature-coils connected therewith. All these parts may be of ordinary 100

construction, well understood by those skilled in the art, and need not be specifically described.

There are two sets of coils upon the field-magnets, one set 8 8 being connected in series with the working-circuit and the other set 9 9 in a shunt around the same, as will herein-after more fully appear. Upon the part of the armature-shaft which projects beyond the frame of the machine are mounted three commutators 10, 11, and 12 side by side and each insulated from the shaft. Each of these commutators is composed of two hollow cylindrical blocks 10' 10², 11' 11², and 12' 12², respectively, each of which blocks is provided at one end with a number of segmental teeth alternating with segmental spaces, and these two blocks are so mounted upon the armature-shaft that the teeth of one engage the corresponding spaces on the other with insulating material, indicated by heavy lines, intervening between the two blocks.

There are two pairs of brushes for each commutator—one pair bearing upon the segmental portions and the other pair upon the continuous cylindrical portions thereof—and in the further description these brushes will be referred to as "alternator-brushes" and "straightener-brushes," respectively.

30 The alternator-brushes 15 15' of commutator 11 are connected with wires 19 19', respectively, which are in turn connected with collecting-brushes 6 6. The alternator-brushes 13 13' of commutator 10 are connected, respectively, with shunt-wires 20 20', which, as will be seen, are across the wires 19 19', or, in other words, across the brush-terminals of the generator. The alternator-brushes 17 17' of commutator 12 are connected with the main or trunk-line 21 21, which is tapped at points 22 22, &c., by multiple-arc branches, in which suitable translating devices 23 23, &c., are included.

One straightener-brush 16 of commutator 11 is connected by a wire 24 with straightener-brush 18' of commutator 12, and the other straightener-brush 16' of commutator 11 is connected by a wire 25 with one terminal of the set of field-coils 8, the other terminal of which is connected by a wire 26 with straightener-brush 18 of commutator 12.

Straightener-brush 14 of commutator 10 is connected by a wire 27 with one terminal of the set of field-coils 9, the other terminal of which is connected by a wire 28 with straightener-brush 14' of said commutator.

It must be understood that the total number of segments of each of the commutators is equal to the number of alternations of current in the generator, and that they are so located upon shaft 5 relative to the coils of armature 4 that one of the alternator-brushes of each of these commutators will bear upon a segment of one of the blocks of which it is composed, while the other of these brushes will bear upon a segment of the other of the

blocks during the prevalence of one electrical impulse.

The circuits can now be easily traced, and the operation will be readily understood.

The alternating currents generated in the armature 4 will leave the same alternately by wires 19 and 19', reaching commutator 11 by one of the alternator-brushes 15 15'. By the operation of this commutator, which is so well understood by those skilled in the art that it need not here be explained, the alternating impulses are straightened out, and, leaving by straightener-brush 16' as a continuous current, the latter passes by wire 25 to and through the set of coils 8 8 of the field-magnets and by wire 26 to commutator 12. The continuous current enters this commutator by straightener-brush 18, and being now again resolved into alternating impulses the latter pass to line 21 and multiple-arc branches 22 22 alternately by brushes 17 17', returning by the other of these brushes, and then by brush 18' and wire 24 to brush 16 of commutator 11, from whence they return by 90 one or the other of alternator-brushes 15 15', and one or the other of the wires 19 19' to the armature 4. The course of the currents generated in the armature thus far described is analogous to the course of a continuous current in an ordinary series dynamo, for it will be observed that the armature, the set of field-coils 8 8, and the main or trunk line 21 21 are all connected in series. There is, however, this important difference, that while in the ordinary dynamo the current traversing the machine and the line is a continuous one, the generator here described furnishes alternating impulses, which are collected and straightened out before they reach the field-coils. The continuous current is then again resolved into alternating impulses which traverse the line. A portion of the alternating currents, passing by wires 19 19' to commutator 11, is diverted to commutator 10 by 100 wires 20 and 20'. These diverted currents reach the commutator 10 by alternator-brushes 13 13', and being straightened out by the operation of said commutator, the continuous current passes by brush 14' and wire 28 to and through the set of field-coils 9 9, which it leaves by wire 27, returning to the commutator by brush 14. This circuit is a shunt across the terminals of the generator, and, as has been seen, it includes the second 120 set 9 9 of the field-coils, which are charged in the same sense as the first set 8 8 of the field-coils, so that the two sets combine to energize the field similar in this respect to the operation of the ordinary continuous-current compound dynamo. The regulating effect of this self-exciting alternating-current generator is also substantially the same as that of an ordinary compound dynamo, as will now be clear to those skilled in the art. If one or more 125 working-circuits are cut out, the external resistance is increased, the total resistance is 130

also increased, but the relation of the external resistance to the total resistance is so varied that the difference of potential is also increased, while less current is generated in 5 the armature and traverses wires 19 19'. The charge of the series coils of the field is therefore weakened, while, by reason of the increased difference of potential, more current is diverted into the shunt-coils; but the 10 aggregate amount of current to the two sets of field-coils is diminished and the strength of the field is decreased. Consequently the difference of potential is lowered. If, on the other hand, more working branches are closed 15 and both the external and total resistances decreased, the relation of the external resistance to the total resistance is so varied that the difference of potential is decreased, while more current is generated in the armature 20 and traverses wires 19 19'. The charge of the series coils of the field is therefore increased, while, by reason of the diminished difference of potential, less current than before is diverted into the shunt-coils; but the 25 aggregate amount of current to the two sets of field-coils is increased and the field is strengthened. Consequently the difference of potential is increased. Thus it will be seen that any change in the system that 30 tends to vary the difference of potential will react upon the dynamo to cause the same to automatically re-establish the original difference of potential.

Alternating-current generators are ordinarily constructed to furnish currents of comparatively very high tension, which currents can be sent to great distances over comparatively thin conductors. Such currents, however, are not well adapted for the operation 35 of the more common translating devices, like motors, lamps, &c., and these currents should be transformed before they reach the motors or lamps into currents of comparatively low tension. For this purpose any suitable trans- 40 former may be used, and in the drawings I have shown induction-transformers 23 23, &c., with their primary coils in the multiple-arc branches 22 22 and their secondary coils in the working-circuits proper; but it will be 45 understood that I am not limited to this arrangement, since any other suitable translating devices adapted to be operated by high-tension currents may be substituted for the induction-transformers. It is also practicable 50 to generate currents of comparatively low tension in the dynamo, in which case lamps

or motors or other translating devices may take the places of the inductoriums in the multiple-arc circuits 22 22.

Numerous changes may be made in the arrangement of the parts of the dynamo without departing from the principle of my invention. It is, for instance, evident that cylindrical block 11² of commutator 11 may be made in one piece with cylindrical block 12² 60 of commutator 12, in which case straightener-brushes 16 and 18' and connecting-wire 24 are dispensed with.

If it is desired to have a continuous current upon the main line, the whole of commutator 12 may be removed and the line extended from wires 24 and 26, as indicated in the drawings by dotted lines 21' 21'; or both circuits may be used, if desired. Other changes of this and a similar character will 70 suggest themselves spontaneously to those skilled in the art, and I desire it to be understood that I do not limit my invention by the identical details of construction herein shown and described.

Having now fully described my invention, I claim and desire to secure by Letters Patent—

1. In a self-exciting alternating-current compound dynamo, the combination, with the armature, of field-magnets having two sets of 85 field-coils wound to act cumulatively in energizing the field, one coil being in series with the working-circuit and the other in a derived circuit, and a separate commutator for each set of coils, said commutators being constructed to straighten the alternating current generated by the dynamo and transform it into two continuous currents for use in energizing the two sets of field-coils, substantially as set forth. 90

2. In a self-exciting alternating-current dynamo, the combination, with a generating-armature and collectors for taking the alternating electrical impulses from the same, of two sets of field-coils and a separate commutator for each set for straightening the alternating exciting-currents to each coil, and an independent commutator for resolving the straightened current into alternating impulses to the line, substantially as described. 95

In testimony whereof I have signed this specification in the presence of two subscribing witnesses.
